UNITED STATES PATENT OFFICE

HANNS STAMMREICH, OF CHARLOTTENBURG, NEAR BERLIN, GERMANY

METAL ARC LAMP

Original application filed July 13, 1928, Serial No. 292,348, and in Germany July 19, 1927. Divided and this application filed August 2, 1930. Serial No. 472,578.

My present invention is a division of my copending application Serial No. 292,348; filed July 13, 1928 and concerns improvements in or relating to the operation of metal arc or metal vapour lamps. My invention has for its object a method of operation avoiding certain disadvantages hitherto inherent to such lamps.

Metallic arcs have various advantages over the ordinary carbon arc and are primarily employed when a light rich in ultra-violet rays is desirable. The most usual form in this case is the mercury-quartz lamp which has the special advantage that no metal is consumed since the mercury distils and condenses inside the arc tube.

However, the energy distribution in the mercury spectrum is such that the light emitted cannot be employed for many purposes; thus it can in general not be considered for lighting purposes because it contains no red. Although its photo-chemical action is certainly considerable, it is, however, extraordinarily decreased by the interposition of glass in the path of the ray, the glass absorbing the greater part of the actinic rays located in the short-wave ultra-violet range. For this reason many applications in photography, for example, are impossible.

An attempt has been made, therefore, to employ in place of mercury metals the spectra of which appear to be especially favourable for the particular purpose in question. Such attempts have, however, encountered technical difficulties caused by the fact that the metals, brought to melting or boiling by the arc, solidify at normal temperatures and either then and there or upon the lamp being set in operation afresh, burst the housing. Furthermore, complications arise in connection with the striking of the arc in the lamp, which, when mercury is employed may, due to its liquid nature, be effected merely by tipping.

In an attempt to avoid these difficulties, while retaining mercury as the lamp filling, other metal has been added thereto. Such amalgam lamps are, it is true, capable of operating, but do not fulfil the desired purpose, since due to the lower melting point

of the mercury, almost exclusively the latter is vapourized in the arc tube and the spectrum of the added metal appears either not at all or very weakly only in comparison with the mercury spectrum.

The present invention makes it possible to use almost all metals in a glass or quartz lamp by employing as the filling in the manner of an amalgam lamp a liquid, pasty, or solid alloy, or a metal mixture, of such a low melting point that the lamp container cannot be destroyed, while the alloy or metal mixture is, during the operation of the lamp, separated into its components in such a manner that the low boiling or undesirable components are distilled out of the arc tube and the metal or metals desirable for the formation of the arc, remain there alone.

After operation, the two components are reunited in the arc tube to form the original alloy.

In the drawing one embodiment of a lamp for carrying out the method of the invention, is represented by way of example.

An arc tube 1 has two branches 2 and 3 closed by means of quartz pieces 4 and 5 through which wires 6 and 7 for the electrical current are led. The quartz pieces 4 and 5 tightly close the branches 2 and 3 so that the amalgam which is contained in two bodies 8 and 9 in the branches 2 and 3 respectively may not flow out. The upper part of the arc tube 1 is connected to a receiver 11 by means of a bent conduit 10.

The operation of the lamp is as follows: When the arc is struck at first only the low boiling mercury is vapourized by the arc and flows through conduit 10 to the receiver 11 where it is condensed. The arc tube 1 being in communication with the receiver or condensation chamber 11, the distillation of the metal does not take place consequently, as in the previous lamps, wholly inside the arc tube but the metal vapourized by the arc distils out of the tube and condenses and remains in the receiver. The size of this receiver preferably is such that it is capable of receiving exactly the amount of metal mercury to be removed from the arc tube, while it causes or allows the other component metal

which is intended to form the arc and part of which may distil over during operation of the lamp to flow back into the arc tube. After operation, the condensate collected in the receiver 11 is returned, by tipping, into the arc tube where the original alloy then forms from the hot metals.

The lamp for carrying the invention into effect may be constructed in different ways. 10 The receiver may, for instance, be provided with means connecting it to the arc tube otherwise than by conduit 10.

I claim:—

15 The method of operating a metal arc lamp, which comprises the steps of heating a metal composition and fractionally distilling it, keeping one component distilled out of said metal composition, out of contact with the remainder of such composition during the 20 operation of the arc lamp, and reuniting the components of said metal composition after the operation of the lamp.

In testimony whereof I have signed my name to this specification.
